UNITED STATES PATENT OFFICE.

MILTON D. WHIPPLE, OF CHARLESTOWN, MASSACHUSETTS, ASSIGNOR TO THE WHIPPLE FILE COMPANY, OF SAME PLACE.

MACHINE FOR CUTTING FILES.

Specification of Letters Patent No. 22,842, dated February 1, 1859.

To all whom it may concern:

Be it known that I, MILTON D. WHIPPLE, of Charlestown, in the county of Middlesex and State of Massachusetts, have invented 5 a new and useful Improved Machine for Cutting Files, of which the following is a full, clear, and exact description, reference being had to the accompanying drawings, making part of this specification, in which—

10 Figure 1, is a plan of the machine—Fig. 2, a side elevation and Fig. 3, an end elevation of the same—Fig. 4, a vertical section through one of the clamping wedges, the file blank and the chisel, on the line x, x , of 15 Fig. 1.

Within the past century repeated attempts have been made to cut files by machinery, but so far as I am informed in no instance has the construction and operation of any 20 machine been made public that was capable of performing its work satisfactorily or of producing files that could favorably compare with those made by hand. Among the difficulties which have thus far proved to be 25 insurmountable in the cutting of files by machinery may be instanced the following:

Firstly the steel of which the files are manufactured is not of uniform structure or hardness and there occur soft and hard 30 places in the blanks and when the chisel was operated by a uniform pressure or by uniform blows of a hammer it was not found possible to give a uniformly roughened surface to the file, as the indentations upon the 35 soft places were much deeper than those upon the hard spots, and a corresponding irregularity of tooth was the result.

2d. A large class of files are wider from the tang to the center than at their extreme 40 end, and it is obvious that a given force whether of pressure or impact that will make the required indenture at the widest part of the file will sink the chisel too deep at the narrower part near the end. Efforts 45 have been made to counteract this difficulty, but thus far without success, by causing the force of the blow to diminish, by diminishing gradually the distance through which the hammer falls, as the work proceeds from 50 the widest to the narrowest part of the file.

3rd. Most files taper in thickness as well as in width, and a further allowance or adjustment is required, to prevent the hammer

from falling through a greater distance when operating upon the thin than on the 55 thick part of the blank.

4th—As the workman when cutting files by hand, adjusts his chisel preparatory to each cut by drawing it back against the bur which constitutes the last tooth made, the 60 leather straps which he employs to hold the blank are sufficient for the purpose—with machine work however it is different, for while it is necessary that the file have a comparatively soft bed on which to rest for 65 the projection of the teeth while the 2d side is being cut, it is equally necessary that this bed be unyielding, otherwise the action of the hammer and chisel upon its surface will vary at different points, and in conjunction 70 with the above requirements there is another still more rigid that the blank be held firmly and immovably that it may be accurately fed between the successive cuts; these conflicting exigencies have placed further difficulties in the path of those who have attempted to cut files by machinery.

In the machines heretofore contrived for making files the side of the blank opposite to that being cut has rested upon an unyielding bed, and as the chisel is held rigidly, if the blank at any part of its length be thicker upon one edge than upon the other, the file will be imperfect at that point owing to the irregular depth of the cut—and it is 85 not found practical without too great an expenditure of labor to forge the blanks so accurately that the opposite sides of their cross sections shall always be parallel.

The above difficulties have all been removed by my present invention which consists:—

Firstly in the employment of a circular chisel which in lieu of being brought up to the blank and forced into its surface by 95 pressure or by the blow of a hammer, is allowed to roll over it; it being so adjusted to the surface of the blank that it shall sink a given distance into it whether it be more or less wide; for it is obvious that the depth 100 of the cut made or the height of bur raised by the tool will not be influenced by the varying width of surface that it is called to act upon. It is also evident if the blank be held rigidly unyielding that the depth 105 to which this cutter will sink into the blank

will not be influenced by the greater or less hardness of the material at different points if it be caused to traverse in a rigidly unyielding plane.

5 Secondly my invention consists in holding that face of the blank which is being cut up against a face plate or rest by pressure upon its opposite side, whereby the position of the side being cut is determined 10 with respect to the cutter, and not that of the side opposite to the one being cut as has heretofore been the case. I thus insure uniformity of cut upon each face of the blank, notwithstanding any difference of 15 thickness that may exist upon the opposite edges or any varying thickness of the blank from end to end. And my invention consists thirdly in clamping the blanks rigidly while a cut is being made, and releasing it 20 preparatory to its being fed, whereby I am enabled to hold it with any required degree of rigidity and to feed it with the utmost accuracy. And my invention consists fourthly in a certain device for holding the 25 blanks while a cut is being made which will be more particularly described hereafter. And my invention consists fifthly in a machine for cutting files consisting essentially of the organization of the above features and so constructed and arranged as to 30 cut files as will now be more fully set forth and described.

In the drawings A, is a bed or table supported upon legs B, B². In suitable bearings at one end of this bed is carried a shaft C, to which is attached the driving pulleys D, a cam E, and a disk F; to the latter is pivoted at a, the connecting rod G' the other end of which is pivoted at b, to a sliding carriage H. This carriage is supported on a way c, which lies horizontally along the side of the bed A, and is secured thereto, the beveled edges 2, 3, of the way fitting into corresponding grooves in the carriage 45 as shown in Figs. 3 and 4. The revolutions of the shaft C, impart to the carriage H, a horizontal reciprocating motion. To the top of the carriage H, is secured a block d, which serves to carry a short shaft e, inclined at an 50 angle of about 45 degrees to the face of the bed A. To this shaft upon its inner end is secured the cutter f, which consists of a circular disk of tempered steel, having a beveled edge, which disk is fastened eccentrically upon the end of the shaft by a screw 4, which passes through the disk into the end of the shaft. A plate g attached to the block d by screws and slots 5, serves as the inner bearing of the shaft e, this plate 55 is adjusted in position by means of the set screw 6, and thus the cutter is raised or lowered to vary the depth of the cut.

To the outer end of the shaft e, is secured a short arm h, connected by a rod i to a 60 lever k, pivoted at 7, to the side of the car-

riage H. A rod l, supported in the legs B, B² carries two adjustable collars or stops m, m², against which the lower end of the lever k, strikes as the carriage H, is traversed back and forth, by which means the shaft e, 70 is caused to make a partial revolution and the cutter f, which as before stated is hung without the center of the shaft e, is brought down to make the cut in the blank as the carriage moves in one direction and is raised 75 up out of the way as the carriage returns that it may not mar the cut just made. The manner in which the blank is held while the cut is being made, and then released and fed up will now be explained. 80

I may here state that the machine which is represented in the accompanying drawings is arranged to cut two files at the same time, but as many may be arranged in front of the cutter f as is found convenient or the 85 traverse of the carriage H, will admit of.

A stout block I, on top of the bed A, has secured to its front edge next to the cutter f, a face plate n, back of which in a suitably inclined slot is placed the file blank q, the 90 face of the blank which is to be cut being in contact with and being pressed against the face plate in the following manner. In a suitable slot cut vertically down through the block I, and bed A, are placed two heavy 95 wedges o, which in addition to their own weight are held down by weights p, suspended from them by rods r, pins 8 in the back of the wedges prevent them from falling too low or binding in their sockets, these 100 wedges are raised at proper intervals to allow the blank to be fed up in the following manner, A shaft K, carried in suitable hangers from the underside of the bed A, has attached to it near one end a lever s, 105 connected with the levers t and u, upon a short shaft v, the lever u, resting in contact with the cam E, on the driving shaft C', so that as the cam is revolved the shaft K, is rocked, and a tappet w, on this shaft 110 strikes the stops 9, on the rods r, and raises the wedges o. A plate x, is secured to the top of the block I, in front of the wedges o; beneath this plate in a suitable slot are inserted two small blocks 10 of metal (partly 115 dotted in Figs. 1 and 3, and in section in Fig. 4,) which bear one against the front edge of each wedge o, and against a shield z, on the rear side of the file blank so that the face which is being cut is pressed against 120 the face plate n. I use two blocks 10, and two wedges o, to each blank, as when the blank is wide they press more equally against both edges of it.

I will now describe the parts of the machine by which the file blank is fed up at intervals after each cut has been made.

A frame L, is secured in an inclined position (to suit the inclination given to the cuts upon the blank) beneath the bed A, 130

(Fig. 2), between the sides of this frame slides a block M, on the front of which is secured a nut q in which turns a screw N, having its bearings in the lower cross piece 5 11, of the frame L. A bevel gear O, on the end of this screw shaft engages with a gear P on a horizontal shaft Q, which carries another beveled gear R, that engages with a gear S, on a vertical shaft T, (dotted in Fig. 10 2.) The shafts Q and T are supported in suitable bearings in the frame work of the machine; the latter extends up through the bed A, and carries on its upper end a ratchet wheel V, the teeth of which are of a proper 15 size to give the required feed. A dog z² held in contact with the wheel V, by the springs 12 and 13, is struck by the incline W, attached to the carriage H, each time the carriage is drawn back in the direction of 20 its arrow, this moves the ratchet wheel V, one notch in the direction of its arrow, and through the shafts T and Q, and their gears turns the screw N and forces up the block M, the required distance, the end of the 25 file blank resting on top of this block as shown in Fig. 2. It should be observed that the wedges o, are raised so as to free the blanks before the feed of the block M, takes place. A handle X attached to the top of 30 the shaft T, serves to turn back the screw N, and lower the block M, when a fresh blank is to be placed in the machine, the dog z² being held out of the way by the operator. The blocks 10 on the side which 35 rests against the wedge o, are rounded as shown in Fig. 4, so that they may always have a proper bearing with the front or flat sides on the shield z, behind the file blank (or a jointed block or shoe may be 40 used). The shield or guard z is a strip of soft metal or of steel plated with soft metal, which is secured to the top of the block M, at 15, (Fig. 4,) behind the blank q, and is fed up with the blank—it is placed in the 45 same slot with the blank and between it and the blocks 10. This presents the face of the file which has been cut from being bruised by the blocks 10 or adhering to them while the second side of the file is being cut. The edge of the blank generally 50 rests against the side of the slot in which it is placed if however it is desired to keep the blank more exactly central in the slot as it is fed up, and thus prevent any slight variation of the angle of the cuts made in it, the blank near its upper end may rest against a pin inserted in the shield z, or the edge of the shield may be turned up a little for it to rest against. 55 The face plate n, is slightly beveled on the side next to the blank so that its upper edge only is in contact with the face of the blank immediately below the point at which the cut is made; thus holding the blank firmly 60 in the immediate vicinity of the cut.

The cutter f, as before stated is secured to the end of the short shaft e, by a screw 4, passing through the center of the disk, this allows the disk or cutter to revolve freely around its center and to roll along over the 70 surface of the blank as it makes each cut, a fresh portion of the edge of the cutter being brought into use by the revolution of the disk.

The face of the blank which is being cut 75 resting against the face plate n, the depth of the cut made by the revolving disk or cutter may easily be regulated, without reference to the width or thickness of the blank.

Operation: The following is the operation 80 of this machine. The block M, is lowered and the blank q, (with the shield z, behind it) is placed in its respective slot in the front of the block I, with its lower end resting on the top of the block M, and its face which is 85 about to be cut bearing against the face plate n, the wedges o, having been previously raised to allow the introduction of the blank, are dropped into place, this binds the blank firmly against the face plate. As the shaft C, is revolved the carriage H, is traversed back and forth on its ways. Starting from the position shown in the drawings the carriage H, is moved in the direction of its arrow, the cutter f is held up 90 out of the way of the blank—the incline W, operates the dog z, and ratchet V, and revolves the shafts T, and Q, and screw N, moving up the block M, and blanks resting on it the required distance. Immediately 95 before this takes place the cam E, through the levers u, t, and s, rocks the shaft K, and raises the wedges o, so that the blank is released to allow it to be fed up. When the carriage reaches the end of its traverse in 100 this direction, the lever k, on the side of it strikes the stop m² and the short shaft e, in the block d is revolved sufficiently to bring the cutter f down so that its lower edge will cut into the blank as the carriage 105 returns, before the carriage commences to move in the opposite direction to make the cut, the shaft K, is rocked in the opposite direction and the wedges o, are lowered into 110 place to hold the blank. The operation is 115 then repeated until the cutting is completed.

What I claim as my invention and desire to secure by Letters Patent is—

1. The circular rolling cutter f operating 120 in the manner substantially as set forth.

2. I claim holding the face of the blank which is being cut up to a face plate or rest by pressure upon its opposite side for the purpose specified.

3. I claim clamping the blank rigidly 125 while a cut is being made and releasing it preparatory to its being fed as set forth.

4. I claim the wedges o, operating as set forth for the purpose of clamping the blanks as described. 130

5. I claim the shield z , against which the blank q rests and which is fed up with the blank in the manner and for the purpose substantially as set forth.
5. I claim the within described machine for cutting files consisting essentially of the combination of the elements above claimed and operating in the manner substantially as set forth.

MILTON D. WHIPPLE.
